TRANSPARENT CLOSURE

Donald W. Dunipace, Perrysburg, Ohio, assignor
to Libbey-Owens-Ford Glass Company, Toledo,
Ohio, a corporation of Ohio

Application December 7, 1942, Serial No. 468,058

6 Claims.

(Cl. 88—1)

My invention relates to curved or bent transparent closures and to the shape or design of such closures to obtain certain predetermined optical advantages.

In the use of curved or bent closures or windows for ordinary glazing purposes, such as in homes, for store fronts, and the like, a deviation in the line of sight is not particularly objectionable. However, in the glazing of observation stations, such as in airplanes, combat vessels, mobile combat units, shore batteries, etc., and especially in those windows or panels through which sighting observations are performed, a relatively small amount of deviation in the line of sight may result in the presence of an abnormal sighting error. For example, tests conducted upon several windows of a given design, having a cylindrical area joined tangentially with a flat area, have shown that sighting errors occur through approximately the same parts of the several windows tested in both $\frac{3}{8}$ inch and $\frac{1}{4}$ inch thicknesses. The sighting errors also corresponded roughly in value for all of the windows. It was found that the amount by which the line of sight was deviated varied from about 0.0 to about 14 mils, varying somewhat from one window to another. When it is recognized that 14 mils corresponds to 42 feet at 1,000 yards, the possibilities of error resulting from the use of such a window for gun sighting becomes apparent. The variation of deviation depends, of course, on the shape of the window and would therefore vary as between different types of curvatures.

The gun sight commonly used in airplanes is ordinarily mounted to swing about a horizontal axis through approximately a 90° arc or, in other words, between a horizontal position and a vertical position. The sighting error in the particular type of window referred to above was found to increase in magnitude as the line of sight was elevated from the horizontal sighting position reaching a maximum value at about 20 degrees elevation and then falling off rapidly to a low value at 35 degrees. Above 35 degrees elevation the sighting error remained relatively slight.

The deviation in the line of sight depends on both the curvature of the glass at any given point and the angle of incidence at which observations are made. If both the curvature and angle of incidence could be held constant, then the deviation would also be constant. In general, this is a practical impossibility since, while it is possible to maintain either of these factors constant, it is not possible to maintain both of them constant at the same time.

I have discovered, however, that it is possible to vary one of these factors in such a way as to compensate for the effect of the other and thus produce a curvature so related to the changing angle of incidence of the line of sight through the window that a maximum amount of change in deviation is obtained. More particularly, I have found that the shape of window which gives the minimum variation of deviation has a curvature along the path of observation closely approximating an ellipse. Although when using an elliptical cylinder neither of the above factors remains constant, yet the curve of the window is so developed that the effect of the variation of the one is offset or counterbalanced by the effect of variation of the other.

A window of elliptical curvature shows a practically constant deviation throughout the sighting range except at the extreme limits or opposite ends thereof. In other words, while there is a deviation resulting from an elliptical bend, the change in deviation is quite small, and actually this small variation occurs at the ends of the sighting range, where presumably the window is used least.

In the accompanying drawing is shown diagrammatically a curved glass window so designed or shaped as to produce a minimum variation of deviation throughout the sighting range.

With reference to the drawing, the two foci or focal points of the ellipse are indicated at f and f' , with the gun sight and more particularly the point of observation being located at the focus f . Upon operation of the gun sight through a 90° arc, the line of sight will pass through the glass window p between the lower limit t to the upper limit t' . After first locating the focus f , which is determined by the point of observation, the locating of the focus f' is determined in the following manner: Focus f' is located at a distance from t' equal to the distance between t and f and at a distance from t corresponding to the distance between t' and f . The major axis of the ellipse has a length of $2a$ equal to the sum of the distances from f to t and f' to t' or the sum of the distances from f to t' and f' to t . The distance between the two foci is $2c$ and the length of the minor axis is $2b$ which is equal to the square root of the difference between the squares of the major axis and the interfocal distance f to f' . Thus, the ellipse is oriented so that its major axis is parallel to the line passing through t and t' and has its focal point f at the point of observation.

With these constants of the ellipse ascertained, the contour of the panel can be determined as, for

example, by the known polar coordinate form of the equation of an ellipse in which:

$$r = \frac{b^2}{a - c(\cos \theta)}$$

Where r is the radius vector of any point on the ellipse and θ is the vectorial angle.

When using a sighting window of the above contour, the variation of deviation throughout the effective range of observation will be minimized due to the relation of the curve of the window to the position of the gun sight. That is to say, the contour of the window and the angle of incidence are so compensated one for the other that a practically constant deviation results. Thus, a line of sight which passes through the ellipse near either focus will strike the surface at a relatively small angle of incidence but the surface will have a relatively large curvature value, whereas a line of sight passing through the elliptical surface remote from the points of the foci will strike at a relatively large angle of incidence and the surface will have a relatively low curvature value. In other words, as the angle of incidence increases the curvature value of the ellipse will decrease and vice versa, so that a change in one factor will be offset or counterbalanced by a change in the other.

For instance, the normal deviation throughout the sighting range of an example where $t' - f$ is a vertical distance of $9\frac{1}{2}$ inches, and $t - f$ is inclined below the horizontal by $6^{\circ}57'$ and has a length of $31\frac{1}{4}$ inches, has been found to be approximately 4.5 mils which is not serious since the gun sight can be harmonized with the gun to compensate for this small deviation which is substantially constant throughout the sighting range. That is, the sight can be adjusted so its image will correspond with the position which the bullets of the gun actually strike.

In addition to minimizing the variation in deviation, this advantage has been accomplished with very little change in the streamlined contour of the window. It should also be noted that this design utilizes glass of substantially constant thickness rather than requiring prescription grinding which would be impractical on window panels of the size ordinarily used in such sighting operations. I have also found that a glass panel of the type herein provided can be readily bent and further that two or more of the panels can be laminated with an interposed layer or layers of thermoplastic to provide a safety glass structure.

The particular design of panel shown in the drawing has, for example, been successfully employed as the sighting window in the gun turret of an airplane, the window being formed from commercial plate glass by bending in a concave mold. However, curved glass panels produced in the above manner can be employed wherever a sighting window having those optical requirements or advantages described above is desired.

Also, while the invention has been described above as being particularly applicable to gun sighting, it would be equally efficient wherever precision observations are carried out. Furthermore, while I have referred particularly to the use of a curved glass panel, it will be understood that the invention comprehends the use of panels of plastic or other transparent materials.

I claim:

1. A curved transparent closure of substantially uniform thickness constituting a window

through which observations can be performed from a predetermined position relative to said window with a substantially constant deviation of the line of sight from said observation position throughout the effective range of observation, said closure comprising a transparent panel having a curvature along a path of observation therethrough approximating a portion of an ellipse passing through two predetermined points on said path, one located on the line of sight at its upper limiting position and the other located on the line of sight at its lower limiting position, one focal point of said ellipse being located at the observation position and the other focal point having a converse geometrical relation with respect to the upper and lower limiting positions on the line of observation as for the first focal point, and said ellipse being so oriented that its major axis is parallel to a line passing through said upper and lower predetermined points and that said observation position is located at the focus nearest the upper predetermined point.

2. A curved transparent closure of substantially uniform thickness constituting a window through which observations can be performed from a predetermined position relative to said window with a substantially constant deviation of the line of sight from said observation position throughout the effective range of observation, said closure comprising a transparent panel having a curvature along a path of observation therethrough approximating a portion of an ellipse passing through two predetermined points in said path, one located on the line of sight at its upper limiting position and the other located on the line of sight at its lower limiting position, said ellipse having one focal point located at the observation position and the other focal point located at a distance from the upper predetermined point equal to the distance between the lower predetermined point and the first focal point and at a distance from the lower predetermined point corresponding to the distance between the upper predetermined point and the first focal point, and said ellipse being so oriented that its major axis is parallel to a line passing through said upper and lower predetermined points and that said observation position is located at the focus nearest the upper predetermined point.

3. A transparent, laminated closure for a vehicle constituting a window through which observations can be performed from a predetermined position within the vehicle with a substantially constant deviation of the line of sight from said observation position throughout the effective range of observation, said closure comprising two sheets of glass and an interposed sheet of thermoplastic material in the form of a transparent panel of substantially uniform thickness having a curvature along a path of observation therethrough approximating a portion of an ellipse, said ellipse being so oriented that its major axis is parallel to a line passing through the opposite limits of the line of sight and that one of the focal points is located at the observation position.

4. A curved transparent closure of substantially uniform thickness constituting a window through which observations can be performed from a predetermined position relative to said window with a substantially constant deviation of the line of sight from said observation position throughout the effective range of obser-

vation, said closure comprising a transparent panel having a curvature along a path of observation therethrough approximating a portion of an ellipse passing through two predetermined points in said path, one located on the line of sight adjacent one limiting position and the other located on the line of sight adjacent its opposite limiting position, said ellipse having one focal point located at the observation position and the other focal point located at a distance from said first mentioned predetermined point equal to the distance between the opposite predetermined point and the first focal point and at a distance from said opposite predetermined point corresponding to the distance between the first-mentioned point and the first focal point, and said ellipse being so oriented that its major axis is parallel to a line passing through said two predetermined points and that said observation position is located at the focus nearest the first-mentioned predetermined point.

5. A transparent, laminated closure for a vehicle constituting a window through which observations can be performed from a predetermined position within the vehicle with a substantially constant deviation of the line of sight from said observation position throughout the effective range of observation, said closure comprising two sheets of glass and an interposed sheet of thermoplastic material in the form of a transparent panel of substantially uniform thickness having a curvature along a path of observation therethrough approximating a portion of an ellipse passing through two predetermined points in said path, one located on the line of sight adjacent one limiting position and the other located on the line of sight adjacent its opposite limiting position, said ellipse having one focal

point located at the observation position and the other focal point located at a distance from said first-mentioned predetermined point equal to the distance between the opposite predetermined point and the first focal point and at a distance from said opposite predetermined point corresponding to the distance between the first-mentioned predetermined point and the first focal point, and said ellipse being so oriented that its major axis is parallel to a line passing through said two predetermined points and that said observation position is located at the focus nearest the first-mentioned predetermined point.

10. In a vehicle having a sight opening, a curved transparent closure therefor constituting a window through which observations can be performed from a position normally occupied by an occupant of the vehicle with a constant deviation of the line of sight from said position throughout the effective range of observation, said closure comprising a transparent panel of substantially uniform thickness having a curvature along the path of observation through said sight opening varying with respect to the predetermined observation position to decrease the curvature value of said line as the angle of incidence of the line of sight from said observation position increases at a rate calculated to overcome the variation in deviation in the line of sight as it passes through said panel and approximating a portion of an ellipse, said ellipse being so oriented as to pass through two points determined by the intersection of the line of sight with the opposite limits of said sight opening and having 20 one focal point located at approximately the normal eye position of an occupant of the vehicle.
